CLAIM

The ornamental design for an identification cardholder, as shown and described.

DESCRIPTION

FIG. 1 is a top plan view of an identification cardholder, showing my new design;

FIG. 2 is a left side elevational view thereof, the right side being a mirror image thereof;

FIG. 3 is a bottom plan view thereof;

FIG. 4 is a rear elevational view thereof; and

FIG. 5 is a front elevational view thereof.

*Fig. 1.**Fig. 2.**Fig. 3.**Fig. 4.**Fig. 5.*
